UNITED STATES PATENT OFFICE.

RAMÓN DE ECHEVARRIA, OF SANTA CRUZ, PHILIPPINE ISLANDS.

COMBINED TOILET ARTICLE.

1,372,609.

Specification of Letters Patent. Patented Mar. 22, 1921.

Application filed March 30, 1920. Serial No. 369,897.

To all whom it may concern:

Be it known that I, RAMÓN DE ECHEVARRIA, a subject of the King of Spain, residing at Santa Cruz, in Tagulaya, Davao, 5 Philippine Islands, have invented new and useful Improvements in Combined Toilet Articles, of which the following is a specification.

This invention has reference to a combination toilet article.

The object of the invention is to produce a toilet article embodying, in a single structure a razor of the ordinary class, a safety razor, a hair cutter, a comb, a screw driver, 15 a nail cutter, a nail file and a shoe buttoner.

The foregoing objects, and others which will appear as the nature of the invention is better understood, may be accomplished by a construction, combination and operative 20 arrangement of parts such as is illustrated by the accompanying drawings.

In the drawings:

Figure 1 is a view of the improvement employed as a comb.

25 Fig. 2 is a view showing the device employed as a double-edge comb.

Fig. 3 is a view of the device employed as an ordinary razor, that is, a razor in which the blade is not protected, one edge of the 30 blade, however, being covered by the toothed element of the improvement, while a portion of the handle is broken away and the pintle 11 is shown in section.

Fig. 4 is a view showing the device employed as a safety razor.

Fig. 5 is a sectional view on the line 5—5 of Fig. 2.

Fig. 6 is a sectional view approximately on the line 6—6 of Fig. 4.

40 Fig. 7 is a sectional view approximately on the line 7—7 of Fig. 1.

Fig. 8 is a perspective view of the main member detached from the handle.

Fig. 9 is a perspective view of the removable member.

Fig. 10 is a perspective view of the wedge member which includes the nail cutter, file and screw driver.

Fig. 11 is a plan view of the blade.

50 As disclosed by the drawings, the improvement contemplates a handle member 10 which comprises spaced sides connected at their outer ends and having at their inner

ends a transversely arranged removable connecting member in the nature of a pintle 11. 55

The pintle passes through a preferably square opening 12 adjacent one end of a shank 13 of my improvement. The end of the shank, outward of the opening 12 is cut or otherwise formed to provide a hook 60 14, and this hook serves as a shoe buttoner. The opening itself, when the main member is removed from the handle may serve as a wrench, but in addition to this the said shank is provided with another square opening 65 which may be larger than the first mentioned opening and which serves as a wrench. This opening is indicated by the numeral 15.

The shank is in the nature of a flat member formed, approximately midway of its 70 length with a depressed or channeled portion that extends to the outer end thereof and which, in reality provides the head for the improvement. This portion of the shank, or what I will refer to as the head is indicated by the numeral 16 and may be formed by stamping the shank. The head, upon the inner edge thereof is formed with a continuous shoulder 17, and from this shoulder extend teeth 18. The inner end of the 80 head also provides a shoulder 19 at its junction with the shank, and the head has spaced substantially rectangular openings 20 therethrough.

The removable member is broadly indicated by the numeral 21 and is in the nature of a comb, having its outer portion or head 22 in the nature of a flat plate but provided, upon its inner edge, and on one of its faces with a ledge or shoulder 23, and from this 85 shoulder portion extend the teeth 24. The head is of a length to be received in the depressed face of the head of the main member and to contact with both the inner and longitudinal shoulders thereon, while the 90 outer edge of the head of the main member is designed to engage with the shoulder or ledge 23 of the member 21, when the members are assembled. The head 22 of the member 21, upon its referred to reduced 100 face is provided with hooks 25 that have their beaks extending in the same direction, and these hooks are designed to pass through the openings in the head.

The locking key comprises a flat plate and 105 is indicated by the numeral 26. This key

- has spaced slots or openings 27 therein which are designed to be arranged longitudinally against the outer face of the head of the main member and to receive the hooks 5 25 of the removable comb member. When the removable member is arranged upon the main member as above described the width of the key member is sufficient to tightly engage with the inner faces of the beak portions 10 of the hooks 25 to hold the sections assembled, but when the parts are arranged to produce other articles such engagement of the key with the hooks would not permit of a space between the members to receive 15 the blade, which will presently be referred to in detail, and therefore I depress one of the faces of the key in a line with one of the end walls of the openings, the said depressions being indicated by the numerals 28. 20 The key, upon one of the faces thereof is serrated to provide a nail file 29, and upon one of the ends thereof is reduced and sharpened to provide a screw driver 30, one of the edges of the reduced portion being sharpened, as at 31 to provide a nail cutter. 25

The blade employed with my improvement is of that class used upon a safety razor of the Durham class and is indicated by the numeral 32. The blade has both of its ends 30 sharpened and is centrally provided with an elongated slot 33. When the blade is to be used upon the device as an ordinary razor the hooks of the removable member are passed through the slot 33 in the said blade. 35 The hooks are also passed through the openings in the head of the main member, and the teeth of the removable member are arranged in the same direction as the teeth of the main member. This permits of the depressed face of the head of the main member being arranged outwardly, and in the said depression the key 26 is arranged. The slots in the key receive the projecting beaks 40 of the hooks 25, and in order to properly 45 compress the elements the beaks of the hooks are received in the depressed portions 28 which align with the openings 27 in the key. It should be stated that the key is of a length approximately equaling that of the 50 head of the removable member and the depressed portion in the head of the main member.

When the device is employed as a safety razor the same is arranged on the removable 55 member as just described, but the removable member is positioned on the main member so that the teeth thereof extend in an opposite direction from the teeth of the main member, or in other words the removable 60 member is positioned as when the device is employed as a double comb. The key is arranged over the outer face of the head of the main member to permit the hooks 25 passing through the openings 27: thereafter the key is moved longitudinally in an in-

ward direction to permit of the inner faces of the hooks being received in the depressed portions 28 of the key.

It is thought that from the foregoing description, when taken in connection with the drawings the simplicity of the construction and the advantages thereof will be apparent without further detailed description.

Having thus described the invention, what is claimed as new, is:—

1. In a device for the purpose set forth, a handle comprising spaced sides having one of their ends connected and a removable pintle at its other end, a slotted shank engaged by the pintle, said shank having an extension providing a head, the said head being depressed from one of its faces and provided with openings, said head having teeth projecting from the shoulder provided by the depression, a removable member including a head having a depressed face and teeth extending from the shoulder provided by the depression, the head of the last mentioned member having hooks extending in the same direction and designed to be passed through the openings in the first mentioned member, and the shoulders of the respective members designed to co-act when the members are arranged in one position, a key member having slots therein designed to receive the beaks of the hooks and to be moved longitudinally to frictionally engage with said hooks and hold the members assembled. 75

2. In combination with a two-sided handle having one of its ends connected and its other end provided with a pintle, of a flat plate including a head and a shank co-extensive with the head, both the head and the shank being slotted and one of the slots of the said shank designed to be engaged by the pintle of the handle, the head having one of its faces depressed to provide a lower and an inner end shoulder, teeth on the head extending from the lower shoulder, a removable member including a flat head having one of its edges provided with an outstanding ledge and teeth projecting from the said ledge, the head of the last mentioned member having hooks extending in the same direction, a slotted blade designed to be arranged between the members and to receive through the slot thereof the hooks of the removable member, said hooks designed to also pass through the openings in the head of the first mentioned member, and a key having slots therein and being depressed in a line with said slots designed to be arranged over the hooks and to be moved longitudinally to bring the depressed portions thereof into frictional engagement with the hooks to retain the first mentioned members assembled. 100

In testimony whereof I affix my signature.
RAMÓN DE ECHEVARRIA.
